UNITED STATES PATENT OFFICE.

JACOB FREDERICK MACER, OF ALLENDALE, ILLINOIS.

CAR-COUPING.

SPECIFICATION forming part of Letters Patent No. 380,399, dated April 3, 1888.

Application filed October 6, 1887. Serial No. 251,640. (No model.)

To all whom it may concern:

Be it known that I, JACOB FREDERICK MACER, a citizen of the United States, residing at Allendale, in the county of Wabash and State of Illinois, have invented a new and useful Improvement in Car-Couplings, of which the following is a specification.

My invention relates to improvements in car-couplings; and it has for its objects the provision of a car-coupling which shall be simple and cheap in construction and positive in operation, the parts of which will be capable of ready replacement when they become worn or broken.

15 A further object of the invention is to produce a mechanism for operating a car-coupling which can be readily and conveniently attached to cars provided with the ordinary means of coupling.

20 A further object is to produce a car-coupling capable of securely coupling cars upon their coming together without the intervention of a hand at the time of meeting, thereby obviating all danger of accidents to persons 25 employed in coupling cars; and, finally, it is my object to produce a car-coupling which will permit the operation of an uncoupling to be performed in an effective manner from either side of the car or from the platform 30 thereof.

With these objects in view my invention consists, essentially, in a car-coupling having a coupling-pin, operating-levers mounted on suitable brackets at the end of the car, the 35 inner ends of the operating-levers being connected to the coupling-pin by links, and guards in which the outer ends of the operating-levers move, said guards being provided with small shoulders or projections, whereby the outer 40 ends of the operating-levers may be engaged when the coupling-pin is raised preparatory to coupling; furthermore, in a car-coupling consisting in a coupling-pin having its upper end provided with a ring having a groove in 45 the top, the operating-levers mounted on suitable bearings and having rings at their inner ends provided with transverse grooves in the upper sides similar to the groove in the ring on the coupling-pin, and the guards in which 50 the outer ends of the levers operate, and, finally, in various novel details of construc-

tion and arrangement hereinafter more fully described, and specifically pointed out in the claims.

In the accompanying drawings, in which 55 like letters of reference denote corresponding parts in the different views, Figure 1 is a perspective view of the improved coupling attached to the end of a car and showing the outer ends of the operating-levers depressed 60 and engaged by the shoulders. Fig. 2 is a detail view of the coupling-pin. Fig. 3 is a detail view of one of the links which connect the inner ends of the levers to the coupling-pin.

65 Referring by letter to the drawings, A designates the draw-head, which is attached in the ordinary way to the end of the car, and is provided with a flared outer end or mouth to guide the front end of the approaching link 70 into the link-cavity. The upper and lower sides of the said draw-head are provided with openings a a' to receive the coupling-pin.

B designates the coupling-pin of the ordinary shape, the upper end of which is provided 75 with a ring, C, having a transverse groove, D, in the top, for a purpose to be explained.

E are brackets bolted to the end of the car and projecting forwardly beyond the projection or platform F on the car, and the extremities of the said brackets are provided 80 with spindles G, screw-threaded at the outer ends to receive the nuts H H.

I represent levers which are mounted at approximately their central points on the said 85 spindles G, and they are secured on the spindles by the nuts H. The inner ends of the operating-levers I are provided with rings or eyes K K, respectively, which eyes are provided at the top with transverse grooves or 90 notches L L, similar to the grooves or notches in the upper side of the ring C.

M M designate links, one or more of which may be used, which connect the eyes on the inner ends of the operating-levers to the ring 95 at the upper end of the coupling-pin. The said rings are provided at one side with an opening where the ends of the bar of which the ring is composed do not come close together, and the said links are designed to be 100 engaged with the eyes K and ring C by passing the thin portions of the said eyes and ring

(formed by the grooves cut therein) through the openings N in the links. It will thus be seen that the inner ends of the operating-levers may be attached to and detached from the upper end of the coupling-link at any time by properly passing the reduced portions of the said eyes and ring through the openings in the links; but the said parts cannot become detached accidentally, as the notches or grooves and openings in the links are so arranged as not to easily come into the proper positions to disengage. In the first place, the reduced portions of the said eyes and ring are arranged in a transverse or horizontal position, while the openings in the links are vertical and cannot assume the horizontal position until the links are turned around, so as to bring the openings entirely out of alignment with the reduced portions.

2c O O designate guards secured to the car body, which are provided with vertical slots P P, in which the outer ends of the levers I operate, and R R are notches formed in the outer sides of the said slots at the bottom, thus providing the shoulders S S, under which to engage the levers.

From the foregoing description it will now be readily seen that to uncouple two adjoining cars it is only necessary to depress the outer end of one of the operating-levers, and thus draw the coupling-pin out of engagement with the coupling-link. After having thus raised the pin out of engagement, the outer end of the lever may be engaged under the shoulder S, and the pin will thus be suspended over the openings a a' in the draw-head in the coupling position. The shoulders S are preferably made very shallow, so as to only insecurely engage the levers, and therefore when a car comes against the end of the car having the raised pin the jar of meeting is sufficient to disengage the lever from the shoulder and allow the pin to fall into engagement with the coupling-link. There is always a slight jar incidental to coupling two cars together, and therefore this manner of forming an automatic coupling is very reliable. In connection with this it may be said that the bearing in the lever which receives the spindle on the end of the bracket E does not fit the said spindle tightly, but is suf-

ficiently loose to allow a slight lateral play, thus giving the jar of coupling more chance to disengage the lever.

Having thus described my invention, I claim—

1. In a car-coupling, the combination, with the draw-head having the aligned openings in the upper and lower sides thereof, of the coupling-pin having a ring, C, on the upper end, the pivoted levers I, having eyes on their inner ends connected to the ring C on the pin by the links M M, and the slotted guards O O, secured to the car near the outer ends of the said levers to guide the vertical motion thereof, substantially as and for the purpose specified. 55

2. In a car-coupling, the combination, with the draw-head having openings a a' therein, of the pin B, to fit in the said openings, the brackets E E, secured to the car and having the spindles G G on the outer ends threaded at the 70 extremities, the levers I I, mounted loosely on the said spindles and held in place by nuts H, screwed on the ends of the latter, the guards O O, secured to the car near the outer ends of the levers and having the slots P to receive 75 and guide the motion of the outer ends of the levers, and the notches R R in the sides of the said slots to receive the ends of the levers in the depressed position, the inner ends of the levers being connected to the upper end of the 80 pin B, all constructed, arranged, and operated substantially as and for the purpose specified.

3. In a car-coupling, the combination, with the draw-head having the openings a a' therein, of the coupling-pin B, having the ring C on the 85 upper end, provided at the top with the transverse groove or notch D, the pivoted levers I, having the eyes K at the inner ends, provided with the transverse notches or grooves L, and the links M, connecting the eyes K with the ring C and having the openings N in the sides thereof, substantially as and for the purpose specified.

In testimony that I claim the foregoing as my own I have hereto affixed my signature in presence of two witnesses.

JACOB FREDERICK MACER.
